PROPELLION MECHANISM FOR CONVEYERS

Curt G. Joa, Sheboygan Falls, Wis., assignor to
 Curt G. Joa, Inc., Manitowoc, Wis., a corpora-
 tion of Wisconsin

Application August 25, 1938, Serial No. 226,625

9 Claims. (CL 271—2.1)

This invention relates to improvements in propulsion mechanism for conveyers. More particularly stated, the invention relates to a device for pulling a web of gauze or the like in which objects may be enfolded.

The invention is of particular utility in the manufacture of sanitary napkins. The present application is a continuation in part of my application 54,669, filed Dec. 16, 1935 which has matured into Patent No. 2,131,808, Oct. 4, 1938, and relating to a sanitary napkin machine.

The object of the invention is to provide means whereby a web may be pulled uniformly in a straight line without slippage and without damage to a soft pad or other object which may be enfolded in the web. Other objects will appear from the following disclosure.

In the drawings:

Figure 1 is a view in side elevation of a propulsion device and cut-off mechanism as used in a sanitary napkin machine and representing one embodiment of this invention.

Figure 2 is a plan view of the structure shown in Fig. 1.

Figure 3 is a view partially in plan and partially in section showing a modified embodiment of my invention particularly adapted for use where the tension to be exerted by the propulsion device is very great.

Figure 4 is a view taken in section on the line 4—4 in Fig. 3.

Figure 5 is a view taken in section on the line 5—5 in Fig. 3.

Figure 6 is a fragmentary detail view in perspective of one of the pressure blocks used in the device illustrated.

Figure 7 is a fragmentary detail view in perspective of one of the mounting plates used to apply pressure in the device shown in Fig. 3.

Like parts are represented by the same reference characters throughout the several views.

In sanitary napkin machines and in other devices where a web of gauze or other material has to be pulled for a considerable distance through the mechanism, the propulsion device which does the pulling must be capable of developing very substantial tension. This is particularly true where the propulsion device operates in synchronism with a cut-off mechanism so that any slippage which may occur between the propulsion device and the web will result in displacing the cut from its desired location in the web. Yet it is also necessary to avoid putting pressure on the web at points where relatively soft pads or

other articles may be enfolded therein and may, perhaps, be damaged by undue pressure.

In the device herein disclosed, a continuous web 8 of gauze in which at spaced intervals pads 9 are enfolded is shown, by way of example, as 5 the type of web for the propulsion of which my improved mechanism is well adapted. The web of gauze, between the enfolded pad, is subjected to the pressure of opposed pressure surfaces of a pair of conveyers 10 and 11. In the device 10 shown in Figures 1 and 2, the conveyor 11 constitutes an endless belt operating over pulleys 12 and 13 and supported on a conveyer table 14 at the point where pressure engagement of the 15 gauze occurs.

The conveyer 10 comprises a pair of spaced chains 15 and 16, corresponding links of which are connected by pressure blocks 17 arranged in series to constitute mutually spaced flexible pressure pads. As shown in Figure 1, this arrangement readily permits the blocks to pass about the sprockets 18 and 19 while maintaining them in closely adjacent positions throughout the series when engaged with the gauze.

The number of pressure blocks employed is 25 such that the length of each flexible pad will correspond substantially exactly to the spacing between the absorbent pads 9 which are enfolded in the gauze web 8. Thus each of the pressure pads 17 of the conveyer will engage only the 30 unfulfilled portion of the gauze, clamping the flat portion of the gauze web tightly to the underlying belt 11. To the extent that the belt 11 is relatively soft, the individual blocks 17 will tend to slightly embed themselves in the belt and the 35 tension which can be exerted by the device may be increased.

If the distance between successive absorbent pads 9 is increased or decreased, a different conveyer 10 will be substituted to have the correct 40 number of pressure blocks to fit the space between the pads. Thus all pressure on the absorbent pads will be avoided and yet a very substantial tension will be rectilinearly exerted upon the gauze to pull it through the mechanism toward the cut-off knife 20 and its co-acting stationary shear 21.

In the device shown in Figures 3 to 7 the gauze web 8 and the enfolded pads 9 are preferably on edge instead of being horizontally disposed. 50 This fact, and the desire to exert an even greater tension on the gauze led to the development of the special design here illustrated.

At one side of the path of the gauze, I provide upper and lower sprockets at 28 and 29. 55

At the other side of the path of the gauze, I provide upper and lower sprockets 30 and 31. The chain 32 which operates over sprocket 28 has its links connected by pintles 33 which are extended to serve also as pintles for the connection of the links of chain 34, which operates over the lower sprocket 28. Similarly, the chain 35 which operates over upper sprocket 30 has its links connected by pintles which are extended at 10 36 to serve also the links of the chain 37 which operate over the lower sprocket 31. Upon the pintles 33 and 36 between the respective upper and lower chains are mounted the pressure blocks 38 and 39, one of which is shown separately in Figure 6. These pressure blocks are 15 identical except for their thickness. They alternate with each other upon their respective chains and are so arranged that a thick pressure block 38 carried by one set of chains at one side of the gauze path is opposite a thin pressure block 39 carried by the other set of chains at the other side of the gauze path. Thus when the gauze is engaged between the blocks of alternating sizes, the gauze is corrugated or convoluted in such a way that the slippage thereof 20 between the pressure blocks is virtually impossible. Therefore, a great deal of tension or pull can be exerted by the device provided the blocks are held in firm pressure engagement upon the 25 gauze.

Such engagement is assured by the pressure bars 40 which are flexibly jointed and resiliently supported by the compression springs 41 at each joint. The bars are mounted in slots 42 of 30 standing guide members 43 disposed at each side of the path of the gauze. Sockets at 44 in guide members 43 receive the compression springs 41. The links of the respective chains ride on the marginal surfaces of the jointed bars 40, thus 35 receiving the pressure of springs 41 and transmitting such pressure through the pressure blocks to the gauze.

In this device the sets of pressure blocks on one conveyer system register exactly with the sets of pressure blocks on the other conveyer system to engage only that portion of the gauze which is intermediate the enfolded pads 8. Therefore, when the pads pass through the propulsive mechanism, they are entirely free of lateral pressure as clearly indicated in Figure 5.

It will, of course, be understood that in each instance means is provided for positively driving the propulsion conveyers as desired. The driving connections are fragmentarily illustrated in Figures 1 and 4 but inasmuch as they may be varied as desired and constitute no part of the present invention, they are not described in detail here.

I claim:

1. A propulsion device of the character described comprising a conveyer and spaced series of pressure blocks mounted thereon, together with co-acting means toward which the pressure of said blocks is directed whereby said blocks are adapted to engage to work under pressure against said means for the propulsion of such work.

2. A device of the character described comprising the combination with an endless conveyer and opposed co-acting pressure receiving means, of guide members encircled by said conveyer and series of pressure blocks mounted at intervals upon the conveyer, said blocks extending transversely thereof and being in close prox-

imity within the series and widely spaced between the series.

3. A device of the character described comprising spaced chains comprising links, guide sprockets for the respective chains, and transversely extending pressure blocks arranged in spaced series and transversely connecting corresponding portions of the respective chains.

4. In a device of the character described, the combination of a pair of propulsion conveyers having proximate flight portions spaced to receive without pressure portions of an intervening web which will not withstand compression, at least one of said conveyers being provided at spaced intervals with series of flexible pads projecting therefrom toward the other of said conveyers for the pressure engagement of work between the conveyers, said pads being close to each other in a given series and said series being comparatively widely spaced from each other.

5. A device of the character described comprising the combination with a pair of conveyers having proximate flights, one of said conveyers comprising a belt and the other of said conveyers comprising a chain, of flexible pressure pads in mutually spaced relation on the chain conveyer and projecting therefrom in a direction to press work toward the belt conveyer in traversing the proximate flights of the respective conveyers, each of said pads on the chain conveyer comprising a series of blocks mounted on successive links of said conveyer.

6. In a device of the character described the combination of a pair of conveyers having proximate flights of pressure, pads spaced on the respective conveyers to register in traversing said proximate flights, said conveyers being materially spaced at said proximate flights between said pads and said pads having relatively greatly and less greatly projecting portions with the greatly projecting portion of the pads of one conveyer in registry with the less greatly projecting portion of the pad of the opposing conveyer whereby to convolute between said pads the work engaged thereby between said flights.

7. In a device of the character described, the combination with spaced mounting members, of conveyers including flights operable in close proximity between said members, flexibly jointed rail means mounted on one of said members and arranged in operative supporting relation to one of said conveyer flights, said mounting member having spring means for the pressure support of said rail means.

8. In a device of the character described, the combination with a support provided with spaced slots, of flexibly jointed rail means mounted in the respective slots, a compression spring mounted upon the support in pressure engagement with said rail means and a conveyer including spaced chains riding on the respective rail means to receive resilient support therefrom.

9. In a device of the character described, the combination with a support provided with spaced slots, of flexibly jointed rail means mounted in the respective slots, a compression spring mounted upon the support in pressure engagement with said rail means, and a conveyer including spaced chains riding on the respective rail means to receive resilient support therefrom, said conveyer including pressure blocks connected with its respective chains and extending transversely therebetween.

CURT G. JOA.
